(57) CLAIM

The ornamental design for an aiming device for improving golf putting and chipping, as shown and described.

DESCRIPTION

FIG. 1 is a perspective view of my new design for an aiming device for improving golf putting and chipping;

FIG. 2 is side elevational view thereof;

FIG. 3 is a rear elevational view thereof;

FIG. 4 is a front elevational view thereof;

FIG. 5 is a top view thereof;

FIG. 6 is a bottom view thereof;

FIG. 7 is a perspective view of a second embodiment of an aiming device for improving golf putting and chipping as disclosed in FIG. 1, wherein the broken-line golf tee illustrated in this figure is not part of the design sought to be patented, and wherein the cross-hatching indicates color;

FIG. 8 is a front elevational view of the aiming device for improving golf putting and chipping of FIG. 7, wherein the cross-hatching indicates color;

FIG. 9 is a top view of the aiming device for improving golf putting and chipping of FIG. 7, wherein the cross-hatching indicates color; and,

FIG. 10 is a bottom view of the aiming device for improving golf putting and chipping of FIG. 7, wherein the cross-hatching indicates color.
